UNITED STATES PATENT OFFICE

ALEXANDER MCLEAN NICOLSON, OF NEW YORK, N. Y., ASSIGNOR TO WIRED RADIO, INC., OF NEW YORK, N. Y., A CORPORATION OF DELAWARE

COMPOSITE PIEZO-ELECTRIC TORSION DEVICE

Application filed December 20, 1926. Serial No. 155,899.

This invention relates to piezo-electric crystal devices more particularly adapted and arranged to be utilized in connection with electric circuits and to a method of producing the same. It has been known for some time that crystals of certain substances, such as Rochelle salt, quartz, tourmaline, and the like, produce an electro-motive force if subjected to physical stress or movement, and conversely, produce physical stresses or movement in response to the impression of an electro-motive force upon them.

Such crystals are capable of wide use and application in the electrical arts, and particularly in those arts which deal with the generation, transmission, and utilization of alternating currents or potentials, whether of audible frequency or of the highest radio frequency.

20 In my Patent No. 1,459,429 issued May 27, 1924, I have shown that Rochelle salt piezo-electric crystals may be used in the generation of electrical oscillations.

In the past, difficulties have been encountered in the use of comparatively large crystals and crystals made by growth from a solution of the mother liquor, such as Rochelle salt crystals. The large crystals, as will be understood, require more time to grow than the small ones, and moreover, they seem to be considerably more fragile and tend to develop cracks and flaws even before the crystals have been effectively cured and hardened.

35 In the case of natural crystals, such as quartz and tourmaline, etc., it is clear that the difficulty and expense of preparing crystals increases greatly with the size, and the liability of accidental injury in the use of the 40 crystal is much greater.

It is an object of this invention to provide a composite piezo-electric crystal, particularly adapted for torsional vibration, and a method of producing the same, whereby the 45 crystal may be given any desired size, shape, and natural frequency, by utilizing fragments of crystals, small crystals, crystal nuclei, and the like, of heterogeneous size and shape, physically secured together to form a 50 single entity and provided with electrodes

so that the piezo-electric effects of the component crystals may be integrated.

It is a further object of this invention to provide a composite piezo-electric crystal particularly adapted for torsional vibration, 55 and a method of producing the same, whereby by crystals of comparatively large size or of unusual dimensions or proportions may be produced, without the delay incident to the growth and curing of such crystals, and without the time, expense, and wastage involved in cutting and grinding the natural crystals.

60 It is still a further object of this invention to provide an improved piezo-electric device of high efficiency and relatively low cost, and 65 one which may be relatively quickly produced. Still other objects of this invention will be apparent from the specification.

The features of novelty which I believe to be characteristic of my invention are set forth 70 with particularity in the appended claims. My invention itself, however, both as to its fundamental principles and as to its practical application, will best be understood by reference to the specification and accompanying drawing, in which:

Fig. 1 is an elevation partly in section of a composite piezo-electric device according to my invention,

Fig. 2 is a diagrammatic view showing one 80 way of assembling the component crystals into a composite structure,

Figs. 3-6 are plan views in section of a composite device according to my invention assembled in different ways.

85 In accordance with my invention, I select a multiplicity of piezo-electric crystals to be assembled into a composite device. The selection is preferably made by choosing crystals which are chemically and optically similar. For example, I may select a number of quartz crystals, being careful to separate the crystals of dextro asymmetry from those of laevo asymmetry. The composite piezo-electric device may be constructed of either of the components, but it is preferable to use in any one composite assembly only crystals of the same asymmetry, as otherwise the mechanical vibrations of the one class will be 90 mechanically 180° out of phase with those of 95 100

the other class, which will interfere with the proper functioning of the device, and may even cause its destruction.

In the case of other hemihedral crystals which occur only in right-handed or left-handed forms, such for example as Rochelle salt, the step of separating the forms is clearly not necessary.

After the component crystals have been selected, I may then proceed to build up a composite structure by arranging the crystals in the desired fashion, being careful to orient each crystal properly with respect to the *c*-axis so that the piezo-electric effects of the various component crystals may be integrated. Since crystals of like chemical and optical form are always analogous to either a right-handed screw thread, or a left-handed screw thread, depending on whether the crystals are dextro or laevo ~~asymmetrical~~, it suffices merely to arrange the crystals with their *c*-axes parallel, and with symmetrical electrodes, for applying or drawing electricity from the component crystals:

The electrodes may comprise plates or metal foil secured to the crystals at proper points forming mechanically and electrically opposite poles. For example, one electrode may comprise an equatorial belt of conducting material forming a loop around the crystal in a plane normal to the *c*-axis, and the other electrode may be attached to the basal plane of the crystal, as more particularly described in the applications referred to above.

Observing this requirement, the component crystals may be assembled into a composite structure in a number of ways. Referring now more particularly to Fig. 1, I have shown a number of crystals 1, 2, 3, 4, etc., assembled into a more or less cylindrical structure, in which there are arranged a number of crystals in line with the *c*-axis which is shown as a dot and dash line. The component crystals herein shown are arranged in any desired manner so as to build up a composite structure of the desired dimensions, by the juxtaposition of the various crystals.

The various component crystals may be secured together physically into a single entity in any desired manner, but I prefer to use a cement of the same elastic properties as those of the component crystals, so that stress waves will be transmitted to all of the components. In the case of Rochelle salt crystals, I prefer to use what I term "Rochelle salt cement" which is described in my Patent No. 1,638,830 issued July 26, 1927, for Rochelle salt composition, or a "melt" of Rochelle salt which has been melted at a temperature controlled according to the amount of water of crystallization it is desired to retain in the melt.

After the composite crystal has been formed, herein shown as a cylinder, it may

be mounted at one end in a base 30, provided with a depression 31 adapted to receive it, and fitted with a cap or stress-distributing member 32, adapted to embrace the other end and rigidly secured thereto, as by cementing. In addition, a plurality of mechanical clamping means, such as flexible tie rods 50 and 51, may be provided passing through the base and cap, threaded to receive nuts 52 and 53 by which the crystal structure may be put under compression. The crystal is now ready for use, and may function either as a generator or motor. That is to say, electromotive fluctuations may be impressed upon it, which will be converted into torsional vibrations of the crystal, such that one end of the cylinder tends to rotate with respect to the other end, or physical stresses may be applied to the crystal tending to rotate one end in a plane normal to the *c*-axis, in order to produce fluctuations of electromotive force corresponding thereto.

Referring now to Fig. 2, I have shown a more regular arrangement of component crystals. In this instance one row of crystals may consist of crystals 10, 11, 12, and 13 all arranged with their *c*-axes parallel, and being arranged in lines normal to the *c*-axes. It will be understood that a plurality of crystals may be arranged also in the same plane with crystals 10, 11, 12, and 13, but normal to the line of those crystals, thereby forming a solid structure in which there are a plurality of crystals arranged in lines normal to the *c*-axis and normal to each other as illustrated more clearly in Fig. 1. A second layer of crystals 14, 15, and 16 may be disposed above the first layer, and an additional layer of crystals 17, 18, 19, and 20 may be arranged. More layers may be added as desired, with the object of bringing the composite structure to the dimensions desired, corresponding electrodes (shown diagrammatically) being provided whereby corresponding poles on the component crystals may be connected together, as for example by means of leads 21, 22, 23 and 24 connected to main lead 28, on the one hand, and leads 25, 26, and 27, connected to main lead 29.

It will be understood that if mechanical stress be applied to the crystal structure of Fig. 2 so as to torsionally stress the crystal about the *c*-axis, an electromotive force will manifest itself upon leads 28 and 29, and conversely, the application of an electromotive force to these leads will cause a corresponding stress of the composite crystal.

Referring now to Figs. 3-6, which are sectional views taken on planes normal to the *c*-axis of the component crystals, I have shown additional ways of arranging the various component crystals so that piezo-electric effects of the component crystals may be integrated. In Fig. 3, it will be noted, the crystals 33 and 34 are arranged in a symmetrical arrangement, the remaining space

being partially or completely filled by the binder such as cement or "melt" 35, if desired.

The arrangement in Fig. 4 is symmetrical, comprising crystals 36—43, and the remaining space being taken by the binder 35 as before. In the arrangement shown in Fig. 5, the various crystals 45₁—45_n are arranged in a ring, the internal and external space being filled by the binder 35.

The arrangement shown in Fig. 6 is a heterogeneous arrangement of crystals 46₁, 46₂, —46_n of varying sizes and shapes, the interstices being occupied by the binder 35.

While I have shown and described certain preferred embodiments of my invention, it will be understood that modifications and changes may be made without departing from the spirit and scope of my invention, as will be understood by those skilled in the art.

I claim:

1. A composite Rochelle salt piezo-electric crystal adapted for torsional vibration comprising a multiplicity of component Rochelle salt piezo-electric crystals chemically and optically similar of heterogeneous size and shape secured together with their *c*-axes parallel by a physically continuous body, said crystals being so connected that piezo-electric torsional vibration of said individual components may be integrated.

2. A composite Rochelle salt piezo-electric crystal adapted for torsional vibration comprising a plurality of component Rochelle salt piezo-electric crystals secured together with their *c*-axes parallel by a physically continuous body and by metallic clamping means embracing a plurality of said crystals, said crystals being disposed in parallel planes and so connected that piezo-electric torsional vibrations of said individual components may be integrated.

3. A composite Rochelle salt piezo-electric crystal adapted for torsional vibration, comprising a multiplicity of component Rochelle salt piezo-electric crystals chemically and optically similar, of heterogeneous size and shape, secured together with their *c*-axes parallel by a physically continuous body, and oriented with respect to each other in planes normal to the *c*-axes and so connected that piezo-electric torsional vibration of said individual components may be integrated.

4. A composite Rochelle salt piezo-electric crystal adapted for torsional vibration, comprising a multiplicity of component Rochelle salt piezo-electric crystals having torsionally vibrating characteristics chemically and optically similar, of heterogeneous size and shape, and a pair of members for securing said crystals in stacked relation, with the *c*-axes of the components parallel, said crystals being so connected that piezo-electric tor-

sional vibrations of said individual components may be integrated.

5. A composite Rochelle salt piezo-electric crystals adapted for torsional vibration comprising a base plate, an end plate, a plurality of Rochelle salt piezo-electric crystals physically secured together with their *c*-axes parallel in superimposed relation between said plates by flexible metallic clamping means extending between said plates, said crystals being so connected that piezo-electric torsional vibrations of said individual components may be integrated.

6. A composite Rochelle salt piezo-electric crystal adapted for torsional vibration, comprising a multiplicity of component Rochelle salt piezo-electric crystals chemically and optically similar, of heterogeneous size and shape, with the *c*-axes of the component crystals parallel and with a plurality of crystals in line parallel to said axis, secured together by a physically continuous body, and so connected that piezo-electric torsional vibrations of said individual components may be integrated.

7. A composite Rochelle salt piezo-electric crystal adapted for torsional vibration comprising a plurality of chemically and optically similar Rochelle salt piezo-electric crystals superimposed one upon another, with their *c*-axes parallel, metallic clamping means engaging the end crystals of said superimposed crystals, said crystals being so connected that piezo-electric torsional vibrations of said individual components may be integrated.

8. A composite Rochelle salt piezo-electric crystal adapted for torsional vibration, comprising a multiplicity of component Rochelle salt piezo-electric crystals chemically and optically similar, of heterogeneous size and shape, with the *c*-axes of the component crystals parallel and with a plurality of crystals in line parallel to said axis and normal thereto, secured in superimposed relation and so connected that piezo-electric torsional vibrations of said individual components may be integrated.

9. A composite Rochelle salt piezo-electric crystal adapted for torsional vibration, comprising a multiplicity of component Rochelle salt piezo-electric crystals chemically and optically similar, of heterogeneous size and shape, with the *c*-axes of the component crystals parallel and with a plurality of crystals in line parallel to said axis and normal thereto, and cemented together by cement having elastic properties similar to those of said component crystals and so connected that piezo-electric torsional vibration of said individual components may be integrated.

10. A composite Rochelle salt piezo-electric crystal adapted for torsional vibration comprising a plurality of chemically and op-

- tically similar Rochelle salt piezo-electric crystals in superimposed stacked relationship with their *c*-axes parallel and with a plurality of crystals in line parallel to said axis and normal thereto, by elastic clamping means engaging said crystals, said crystals being so connected that piezo-electric torsional vibrations of said individual components may be integrated.
- 10 11. A composite piezo-electric crystal adapted for torsional vibration, comprising a multiplicity of component piezo-electric crystals characterized by having torsionally vibrating properties and being chemically and optically similar, of heterogeneous size and shape, with the *c*-axes of the component crystals parallel and with a plurality of crystals in line parallel to said axis and normal thereto, said crystals being cemented together by a cement having elastic properties similar to those of said component crystals, and so connected that piezo-electric torsional vibrations of said individual components may be integrated.
- 15 12. A composite piezo-electric device adapted for torsional vibration comprising a multiplicity of component piezo-electric crystals characterized by having torsionally vibrating properties and being chemically and optically similar of heterogeneous size and shape, means for securing said crystals in superimposed relationship, cement having elastic properties similar to those of said component crystals comprising means for uniting said crystals, with the *c*-axes of the component crystals parallel, the faces of abutting crystals being so connected that piezo-electric torsional vibrations of said individual components may be integrated, and
- 20 40 means for applying compression to said composite device.
13. A composite piezo-electric device adapted for torsional vibration comprising a multiplicity of component piezo-electric crystals characterized by having torsionally vibrating properties and being chemically and optically similar, of heterogeneous size and shape, a cement having elastic properties similar to those of said component crystals for uniting said crystals in superimposed relationship, with the *c*-axes of the component crystals parallel, the faces of said crystals being so connected that piezo-electric torsional vibrations of said individual components may be integrated, and means for applying compression to said composite device along the line of the *c*-axis of the component crystals.

In testimony whereof I hereunto affix my
60 signature.

ALEXANDER McLEAN NICOLSON.
